CHARLES EMILE GERBAUD, OF PARIS, FRANCE.

SPARKING PLUG FOR INTERNAL-COMBUSTION ENGINES AND METHOD OF MANUFACTURING THE SAME.

1,347,367.

Specification of Letters Patent. Patented July 20, 1920.

Application filed February 24, 1919. Serial No. 278,694.

To all whom it may concern:

Be it known that I, CHARLES EMILE GERBAUD, of 102 Rue Pelleport, Paris, France, manufacturer, have invented an Improved 5 Sparking Plug for Internal-Combustion Engines and Method of Manufacturing the Same, of which the following is a clear, exact, and full description.

The object of this invention is to provide 10 a sparking plug for an internal-combustion engine, the constituent parts of which are so united as to form a single integral piece, which will have for effect to obviate the leakage of gas or lubricating oil.

15 A further object of this invention is to provide a plug capable of withstanding very great temperature and very heavy pressure, while always remaining completely insulated.

20 The characteristic features of my improved plug (which is made in the manner hereinafter described) are:

1. The insulating body cast on to the central rod forming the axial electrode, and
- 25 2. The metallic shell formed of a mass of metal cast on to said insulating body.

Figure 1 of the accompanying drawing shows, in central vertical section and by way of example, one form of the single-piece 30 plug.

Figs. 2 and 3 illustrate the mold in which the insulating body is cast, Fig. 2 being an elevation of the inner face of one half of the mold, the insulating body being shown 35 in section, while Fig. 3 is a plan of the mold.

Figs. 4 and 5 represent the mold in which the metallic shell is cast, Fig. 4 showing the inner face of one half of the mold, the metallic shell being shown in section, while 40 Fig. 5 is a plan of the mold.

As is shown in Fig. 1, my improved plug comprises an axial rod *a* of the usual form, constituting one of the electrodes, an insulating body *b* cast on said rod, and a metallic shell or body *c* cast on the insulating body.

The insulating body *b* may be made of sodium boro-silicate of the following composition, viz: sand 58 parts; soda 15 parts; 45 boric acid 60 parts; potassium nitrate 6 parts; with the addition of oxids necessary to give the body the desired color.

It should be understood, however, that this formula is only given by way of ex-

ample, and that any other composition or 55 insulating material may, if desired, be used.

The shell *c* is formed of a metal or metallic alloy, which can be readily poured, say, an alloy having the composition: zinc 75%; aluminium 15%; copper 10%. 60

The plug is made as follows:

The rod *a*, intended to serve as the axial electrode, is placed in a metal mold, similar to the molds used in glass making, (consisting of two shells *d* hinged together—Figs. 65 2 and 3—and provided with an internal cavity corresponding in shape to the shape desired for the insulating body *b*), and, when the mold is closed, the sodium borosilicate is poured in through the gate *e* and 70 is then compressed by means of a tamping iron *f* or by a press.

When this casting process has been completed, the insulating body *b* is taken out of the mold and the surplus material *b'* is 75 cut off.

The insulating body *b*, provided with the axial electrode *a*, and while in a plastic state is then placed in a second metal two-part mold *g* (Figs. 4 and 5), each member 80 of which is furnished with a handle and fits one against the other, and provided with an internal cavity which corresponds in shape to that of the metallic shell *c*. This mold is provided with a two-part core *h*, *i* for enabling the tubular portion of the metallic body of the plug to be cast. *j* is the gate through which the metal is poured into the mold. 85

The plug is then complete, and it only remains to true up the screw thread (if necessary) and mount the electrode. 90

By casting the shell on the insulating body while the body is in a plastic state, there is a complete adherence of the metal shell to the insulating body, and as the metal of the shell contracts, on cooling, more than the material of the insulating body, the shell is held in close contact with the said body so that there is no possibility of 95 leakage between the parts. Then again owing to the insulating body being hot when the shell is cast thereon, there is no likelihood of the insulating body being broken as would likely happen if the shell was cast 100 on a cold insulating body. 105

As these two casting processes are effected while the masses are hot during the entire

operation, it will readily be understood that, after cooling, the three constituent parts of the plug will be intimately united so as to form a single structure.

- 5 The shape and dimensions of the various members of the improved plug, as well as the materials of which they are made, may be modified.

Claims—

- 10 1. The herein described process for manufacturing spark plugs, for explosion motors consisting in casting a glass insulator on a metal rod which forms an electrode and then immediately while the insulator is in a plastic state, casting a metal shell on the insulator.
- 15 2. The herein described process for manufacturing spark plugs for explosion motors, consisting in casting an insulating body

formed of borax-silicate upon a metal rod 20 which forms an electrode, and then immediately while the insulator body is in a plastic state, casting a metal shell upon the insulator body.

3. The herein described process for manufacturing spark plugs for explosion motors, consisting in casting an insulating body on a metal rod which forms an electrode, and then immediately while the insulating body is in a plastic state, casting an alloy of 30 zinc, aluminium and copper on the insulating body.

The foregoing specification of my improved sparking plug for internal-combustion engines and method of manufacturing 35 the same, signed by me this 27th day of January 1919.

CHARLES EMILE GERBAUD.
